(57) **CLAIM**

The ornamental design for a gel ice hat, as shown and described.

DESCRIPTION

FIG. 1 is a front and top perspective view of a gel ice hat, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view thereof, shown in a using position.

The broken lines showing of a human head in FIG.9 depict environmental structure that form no part of the claimed design.

1 Claim, 9 Drawing Sheets
